UNITED STATES PATENT OFFICE.

OLIVER P. FRITCHLE, OF DENVER, COLORADO, ASSIGNOR TO THE FRITCHLE AUTOMOBILE AND BATTERY CO., OF DENVER, COLORADO, A CORPORATION OF COLORADO.

DESIGN FOR A VEHICLE-BODY.

42,278.

Specification for Design.

Patented Mar. 12, 1912.

Application filed December 1, 1911. Serial No. 663,453. Term of patent 14 years.

To all whom it may concern:

Be it known that I, OLIVER P. FRITCHLE, a citizen of the United States, residing at Denver, in the county of Denver and State of Colorado, have invented a new, original, and ornamental Design for Vehicle-Bodies, of which the following is a specification, reference being had to the accompanying drawing, forming part thereof.

The figure is a perspective view of a vehicle body, showing my new design.

I claim:

The ornamental design for a vehicle body, as shown.

OLIVER P. FRITCHLE.
